UNITED STATES PATENT OFFICE

REGINALD B. WOODCOCK, OF LEICESTER, ENGLAND, ASSIGNOR TO UNITED SHOE MANUFACTURING CORPORATION, OF PATERSON, NEW JERSEY, A CORPORATION OF NEW JERSEY

HOT-ROLL BOTTOM-BURNISHING MACHINE

Application filed October 28, 1928, Serial No. 314,485, and in Great Britain November 15, 1927.

This invention relates to machines for finishing leather and particularly the leather bottoms of boots and shoes. As herein shown, it is embodied in a machine for wax finishing such leather and includes a wax-applying roll and a series of driven burnishing rolls.

It has been found that in machines of this character the most convenient arrangement for the operator, enabling him to handle the work most expeditiously, is that in which the burnishing rolls are arranged side by side at substantially the same height and with their working faces approximately in alignment. Such a machine is shown in copending application Serial No. 219,954, filed September 16, 1927. In one aspect the present invention consists in a further development or carrying-forward of machines of that type in respects which render them more flexible in the adjustment of their component parts and more convenient in maintenance.

In another aspect the invention consists in improvements in finishing machines which are of general application. The waxes commonly used for burnishing purposes may be most conveniently applied to the work by means of rolls having absorbent surfaces upon which the wax must be rendered molten and for this purpose felt rolls with textile-covered surfaces are preferred. As felt is a poor conductor of heat, it is desirable to provide a heating medium coextensive with a portion of the periphery of the roll and acting to melt the wax on the surface thereof by radiation. In accordance with an important feature of the invention, it is proposed to support the driven wax-applying roll in position adjacent to the heating member by supporting means which are movable to carry the roll bodily toward or from the heating member and without disorganizing the driving connections to the roll. With such a construction the roll may be moved away from the heating member whenever it is desired to get unhampered access to the roll to replace the cover thereof. The proper adjusted relation between the roll and the heating member may also be easily established and maintained. As herein shown, a forming roll is employed for shaping the surface of the wax-applying roll and

this is preferably mounted in the heating member so that the capacity for movement above referred to permits also of adjusting the wax-applying roll properly with respect to the forming roll.

Another feature of the invention consists in a series of aligned wax-finishing rolls arranged to be driven as separate units in which an intermediate unit is mounted so that it may be displaced bodily out of line with the remaining units. It will be understood that where the various rolls are arranged side by side and with limited space between them it is inconvenient for the operator to remove and replace the cover of an intermediate burnishing roll on account of the close proximity of the adjacent rolls or their driving connections. This invention, accordingly, contemplates a mounting for such a roll permitting it to be displaced substantially out of line with the adjacent rolls so that its end surfaces are exposed and may be conveniently reached. As herein shown the intermediate roll is carried by a pivotally mounted bracket releasably maintained in operative position and provided with means for locking or releasing the bracket and with means for counter-balancing it when it has been unlocked and released.

Still another feature of the invention relates to a novel mounting for a shank pad affording a capacity for adjustment to suit the preference of the individual operator. As herein shown this is provided for by mounting the shank pad on a slide movable obliquely from front to rear and also bodily movable in a vertical direction. The shank pad is preferably located somewhat above and in front of the line of burnishing rolls and, accordingly, the mechanism above described serves to permit adjustment of the pad toward and from the line of the burnishing rolls without disturbing their driving connections.

These and other features of the invention will be best understood and appreciated from the following description of a preferred embodiment thereof, selected for purposes of illustration and shown in the accompanying drawings, in which

Fig. 1 is a view in front elevation, certain

parts being broken away, of a machine in which the invention is embodied,

Fig. 2 is an end elevation, certain parts being broken away,

Fig. 3 is a plan view, partly in section; and

Fig. 4 is a view in side elevation of one of the intermediate burnishing rolls.

The machine illustrated in the drawings comprises a frame which includes a horizontally disposed bed 9 and legs for supporting the same. At the right-hand end of the bed, as seen in Figs. 1 and 2, is provided a stand or bracket 8 for the wax-applying roll 1. The roll is of a yielding character, having a textile cover, and is herein shown as concaved in contour. It is journaled to run upon a shaft 4 and carries a sprocket wheel 5 by which it may be driven from any convenient source of power through the medium of a sprocket chain. The shaft 4 is provided with an offset or eccentric portion 6 which is received in a bore formed in the bracket 8 and may be locked in any position of adjustment by a clamping screw 7 threaded into the upper portion of the bracket and bearing upon the eccentric portion 6 of the shaft.

The roll 1 is adapted to carry melted wax upon its surface and apply it to the work in the manner well known. In order to maintain the wax in molten condition, a curved heating member comprising a casing 2 is arranged to extend about the rear portion of the periphery of the roll 1 and in close proximity thereto. The casing 2 may be heated by any convenient means such as steam, hot oil or electricity. At its upper end the heating member is provided with bearings for an idle forming roll 3 having a convex curvature which is the reverse of the curvature desired in the face of the wax-applying roll. The heated casing 2 is adjustably mounted upon a slide 10 by a pair of bolts extending through curved slots in a flange on the casing so that the casing and the forming roll may be adjusted angularly in respect to the wax-applying roll 1. The slide 10 is mounted in a guideway formed in the bracket 8 and is adapted to be locked in any position of adjustment from front to rear by a hand screw 11.

It will be understood that by loosening the clamping screw 7 the shaft 4 with the roll 1 is rendered free to move about the axis of the eccentric portion 6 of the shaft. In this way it may be swung forwardly from the heated casing 2 and out of engagement with the forming roll 3 whenever it is desired to change the renewable cover of the roll, an operation which could not otherwise be carried out on account of the close proximity of the heater and forming roll. Moreover, since the driven sprocket wheel 5 is carried with the roll 1 the driving connection to the roll is not disturbed.

To the left of the wax-applying roll 1 is

located a bottom burnishing or polishing roll 12. This roll is also of a yielding character and provided with a textile cover although it is not usually heated. The burnishing roll 12 is mounted upon the right-hand end of a shaft 14 which carries also a driving pulley 16 and at its other end a conical shank burnishing or polishing roll 13. The shank burnishing roll is disposed with its larger end nearest the bottom burnishing roll 12. The shaft 14 is journaled in ball bearings 15 which are mounted in the free end of a bracket 17 pivotally mounted or hinged to the bed 9 upon a transverse pin 18. The bracket, therefore, may be swung about the axis of the pin 18 forwardly and downwardly, carrying the shaft 14 with the rolls and pulley mounted thereon and in no way interfering with the driving connection beyond slackening of the belt which drives the pulley 16.

The bracket 17 is maintained normally in its operative position by a releasable connection with the rear side of the bed 9, which includes a rocker lever 23 pivoted upon a pin 24 to the bed 9 and having a socket to receive a threaded locking bolt 19. The lock bolt 19 has a hand wheel 20 at its upper end and an intermediate collar 21 which is arranged to engage a pair of lugs 22 projecting from the rear side of the bracket 17. When the lock bolt 19 is screwed into its socket so that the collar 21 bears upon the lugs 22 the bracket 17 is held rigidly with the shaft 14 in operative position. When it is desired to release the bracket 17 to permit its forward movement the lock bolt 19 is loosened and thereupon it is swung toward the rear and out of engagement with the lugs 22 by a spring 25 secured to the lower end of the rocker lever 23. Movement of the rocker lever under the actuation of the spring 25 is limited by a stop face 26 on the lever which is arranged to contact with a corresponding face 27 on the frame 9. The spring 25 being secured also to the bracket 17 acts to counter-balance the weight of the rolls when the bracket is swung forwardly and downwardly. The forward swinging movement of the bracket 17 is limited by a pair of lugs 28 on the bed 9 with which it comes in contact.

To the left of the shank burnishing roll 13 is located a bracket 31 (Fig. 1) having bearings for a shaft 30 which carries a rotary brush 29 at its outer end and a driving pulley 32 at its inner end. The pulley 32 is driven independently of the other finishing rolls by a belt from any convenient source of power. The axis of the brush shaft 30 is located substantially in the same horizontal plane as that of the burnishing roll shaft 14 when the latter is in its operative position but somewhat to the rear thereof, so that the working face of the brush 29 is in approximately the same vertical plane as the work

face of the burnishing rolls and the wax-applying roll.

The bracket 31 is provided with a vertical bore to receive the stem 51 of a vertically adjustable holder 39 which is formed at its upper end with a slideway 40, as shown in Figs. 2 and 3, inclined upwardly and forwardly. The body of the bracket 31 is split at its rear side and a clamping bolt 52 provided for clamping the holder 39 in any position of vertical adjustment. In the slideway is located an elongated slide 36 longitudinally slotted and adjustably secured in place by a clamping bolt 38 which passes through it and is threaded into the upper portion of the holder 39. At the forward end of the slide 36 is adjustably secured a bearing member 35 by means of a clamping bolt 37. The bearing member is provided with bearings 20 for a pad shaft 34 having a tight pulley 42 and a loose pulley 41 mounted on its upper end and carrying at its lower end a flexible rotary pad 33 for burnishing the shank of the sole close to the breast and also the breast face of the heel. The pad herein shown is similar in construction to that disclosed in pending application Serial No. 102,688, filed April 17, 1926, by Ricks and Towndrow. The holder 39 and slide 36 are so proportioned and designed as to position the shank pad 33 about midway between the shank burnishing roll 13 and the brush 29, somewhat above and slightly in advance of these rolls and with the axis of its shaft inclined at an angle of about 60° to the horizontal. The pad shaft 34 is driven by a belt 43 led over idlers journaled at the lower end of the slide 36 to any convenient source of power.

It will be apparent that the bearing member 35 may be angularly adjusted on the end of the slide 36 and maintained in any position of angular adjustment by the clamping bolt 37. The pad may be adjusted forwardly and rearwardly at an inclination by loosening the clamping bolt 38 and shifting the position of the slide 36 upon the holder 39. Finally, the pad with the slide 36 may be adjusted vertically by loosening the clamping bolt 52 and changing the position of the stem 51 in the bracket 31. The pad, therefore, may be located in whatever position preferred by the operator and in the most convenient relation for him with respect to the shank burnishing roll 13, the work of which the shank pad supplements.

It will be apparent that the foregoing invention provides a machine for carrying out the complete operation of wax-finishing a shoe bottom and that the instrumentalities employed are located advantageously in proximity so that the operator may carry the work rapidly from one roll to another. It will be apparent that the various rolls of the series are located side by side in approximate alignment and so close together that the operation

of renewing a cover of the burnishing roll 12 or the shank roll 13 would be inconvenient on account of the close proximity of the bracket 8 on the one side and the driving pulley 32 on the other. This difficulty is avoided and the maintenance of the machine facilitated by mounting the intermediate unit of the three driven units for displacement, as above explained, to an inoperative position substantially out of line with the other rolls of the series and their driving connections. The novel mounting of the wax-applying roll 1, whereby the movement of displacement is made possible, is useful in facilitating the renewal of the roll cover and also in establishing the proper relative adjustment of the wax-applying roll and its associated heating member and forming roll.

Many modifications and changes in detail will readily occur to those skilled in the art without departing from the spirit and scope of my invention, but having set forth the objects and nature of the invention, and having shown and described a construction embodying the features thereof, what I claim as new and desire to secure by Letters Patent is:

1. In a finishing machine, a heated casing, a driven wax-applying roll, and means for supporting said roll in position adjacent to said casing movable to carry the roll bodily toward or from the casing.
2. In a finishing machine, a heated member carrying a forming roll, a driven wax-applying roll, and means for supporting said roll in position adjacent to said heated member and in contact with said forming roll movable to permit said driven roll to be separated from said heated member and said forming roll.
3. In a finishing machine, a heated member, a forming roll rotatably mounted thereon, a driven wax-applying roll, and a shaft located in position to maintain said wax-applying roll in operative relation to said heated member and roll, said shaft having an eccentric support whereby it may be displaced to carry the roll bodily to an inoperative position.
4. In a finishing machine, a driven wax-applying roll, a heated segmental casing shaped to correspond substantially to said roll, being circumferentially adjustable relative thereto and carrying a forming roll, and means for independently supporting and driving said wax-applying roll.

5. In a finishing machine, a plurality of wax-finishing rolls arranged in approximately axial alignment and driven as three separate units, the intermediate unit being mounted so that it may be displaced bodily out of line with the remaining units.

6. In a finishing machine, a plurality of wax-finishing rolls arranged in approximately axial alignment, driven as three separate

- units and having each a driving connection, and means for releasably maintaining the intermediate unit in position arranged to permit it to be displaced transversely with its driving connection from the line of the rolls.
7. In a finishing machine, a series of driven finishing rolls arranged with their operative faces in substantial alignment, a bracket for one of the intermediate rolls of said series pivotally mounted to move transversely to the line of the rolls, and means for releasably maintaining said bracket in position.
8. In a finishing machine, a series of driven finishing rolls mounted side by side, a hinged bracket in which one of the intermediate rolls is mounted, means for locking said bracket in position and a spring operative to counter-balance said bracket when it has been unlocked.
9. In a finishing machine, a series of driven finishing rolls mounted side by side, a hinged bracket for one roll having a locking projection, a pivoted arm having a co-operating locking member, and a spring connected to said arm for moving the arm to unlocking position and counter-balancing the bracket.
10. In a finishing machine, a frame, a bracket pivotally mounted thereon and carrying at its free end a driven shaft, a burnishing roll mounted on said shaft and having a renewable textile cover, and releasable means for maintaining said bracket in operative position arranged to be disengaged to permit the bracket to be tilted to present the roll in an inoperative position where its cover may be replaced.
11. In a finishing machine having a series of driven finishing rolls, a shank pad with driving connections located above and in front of the other pads of the series, and a mounting therefor constructed and arranged to permit adjustment of the shank pad bodily forwardly and rearwardly in an inclined path, and bodily in a vertical direction.
12. In a finishing machine, a frame, a bracket vertically adjustable upon the frame, an obliquely inclined slideway carried by the bracket, a slide adjustably retained in said slideway and having bearings therein, and an inclined shank pad shaft mounted in said bearings and carrying a flexible shank pad.
13. In a finishing machine, a bed, a driven wax-applying roll mounted at one side of the bed, a driven brush mounted at the other side of the bed, and a bracket arranged to maintain a driven polishing roll in operative position substantially between the wax-applying roll and brush and being so mounted as to permit bodily movement of said driven polishing roll transversely to an inoperative position.
14. In a finishing machine, driven finishing rolls mounted in spaced relation, and an intermediate forked bracket having a shaft with a driving pulley located between the arms thereof and a burnishing roll on either end of the shaft, said bracket being arranged to move to carry said shaft with its pulley and rolls as a unit to an inoperative position remote from said spaced finishing rolls.
15. In a finishing machine, a frame, driven finishing rolls located side by side in close proximity upon the bed and having separate driving connections, and brackets for supporting said rolls, one of said brackets being movably mounted upon the frame whereby it may be moved to present its finishing roll in an inoperative position out of line with the adjacent roll.
- In testimony whereof I have signed my name to this specification.
